UNITED STATES PATENT OFFICE.

ALFRED J. MEDLAR, OF PHILADELPHIA, PENNSYLVANIA, ASSIGNOR TO THE
A. J. MEDLAR COMPANY, (LIMITED,) OF SAME PLACE.

DESIGN FOR A CRACKER OR BISCUIT.

SPECIFICATION forming part of Design No. 15,211, dated August 5, 1884.

Application filed March 10, 1884. Term of patent 3½ years.

To all whom it may concern:

Be it known that I, ALFRED J. MEDLAR, a citizen of the United States, and a resident of Philadelphia, Pennsylvania, have invented or 5 produced a new and original Design for a Cracker or Biscuit, of which the following is a specification.

My design is fully shown in the accompanying drawings, in which Figure 1 is a perspective view of the cracker, and Fig. 2 an end view of the same.

The design comprises the representation of a clam with the shells closed.

In my Design Patent No. 13,909, May 15, 1883, 15 is shown and claimed the representation of the single shell of a clam; but the present design

is distinct from this, in that both shells are shown closed against each other, so that only the outside of each shell is visible.

I claim—

The within-described design for a cracker or biscuit, said design consisting of the representation of a clam with the shells closed, as shown and described.

In testimony whereof I have signed my name 25 to this specification in the presence of two subscribing witnesses.

A. J. MEDLAR.

Witnesses:

HARRY SMITH,
WILLIAM C. KLEINORT.
